UNITED STATES PATENT OFFICE.

JULIUS HILDER, OF NEW YORK, N. Y.

DESIGN FOR A BELT ATTACHMENT.

SPECIFICATION forming part of Design No. 33,401, dated October 16, 1900.

Application filed June 11, 1900. Serial No. 19,966. Term of patent 3½ years.

To all whom it may concern:

Be it known that I, JULIUS HILDER, a citizen of the United States, residing in New York city, borough of Manhattan, State of New York, have invented and produced a new and original Design for Belt Attachments, of which the following is a specification, reference being had to the accompanying drawings, forming part hereof, wherein—

10 Figure 1 is a face view of a belt attachment embodying my design, and Fig. 2 is an edge view looking from the right in Fig. 1.

15 The leading or material feature of my design consists in the configuration of a belt attachment in which two vertically-disposed arch-like members, located side by side, have their convex edges facing each other and their concave edges facing in opposite directions.

In the drawings the letters A B indicate the vertically-disposed members of the belt attachment, which are located side by side and are each arch-like or concavo-convex, the convex edges *a b* of which face each other, and their concave edges *a' b'* face in opposite directions or outwardly.

20 25 As shown in Fig. 2, the members A B are curved laterally.

I claim—

The design for a belt attachment, as herein shown and described.

JULIUS HILDER.
